UNITED STATES PATENT OFFICE.

THOMAS A. CASEY, OF NEW YORK, ASSIGNOR, BY MESNE ASSIGNMENTS, TO WILLIAM WALLACE AND GEORGE A. PORTER, BOTH OF SYRACUSE, NEW YORK.

RAILWAY-SIGNAL.

SPECIFICATION forming part of Letters Patent No. 403,515, dated May 21, 1889.

Application filed July 18, 1888. Serial No. 280,248. (No model.)

To all whom it may concern:

Be it known that I, THOMAS A. CASEY, of New York, in the county of New York, in the State of New York, have invented new and useful Improvements in Railway-Signals, of which the following, taken in connection with the accompanying drawings, is a full, clear, and exact description.

This invention relates to the class of railroad-signals which electrically register the number of cars passing over a certain section or block of the road and simultaneously produce a visual signal indicating the passage of said cars into and out of said block of road, and it has special reference to the railway-signaling apparatus for which J. Harper Gibson has obtained Letters Patent of the United States No. 375,063, dated December 20, 1887. In the apparatus shown in said patent the circuit had to pass through the registering mechanism and its supporting-frame, and the signal was not cut out of the circuit and set to indicate "danger" until the car-wheel had passed over the track-instrument and allowed the circuit to reclose. In practice it is found that such arrangements do not actuate the signal as promptly as desired and a very slight variation in the required movements of the registering mechanism or slight displacement of the electric contact-points thereof is liable to cause a failure of the operation of the signal.

The object of this invention is to operate the signal independently of the operation of the registering mechanism and by the first break of the circuit by the track-instrument, and thus render the operation of the signal more positive and quicker than by the aforesaid prior devices; and to that end my invention consists, essentially, in the combination, with the electro-magnetic registering and signaling mechanism in the same circuit, of a shunt in said circuit operated by the armature of the magnet of the registering mechanism and independently of said mechanism, and thereby cut the signal out of the circuit by the first movement of said armature, as hereinafter more fully described, and specifically set forth in the claims.

I do not limit my invention to its applica-

tion to any specific form of registering mechanism or signal, although it is in some respects specially adapted for those shown in the patent to J. Harper Gibson hereinbefore mentioned, and which is to some extent illustrated 55 in the accompanying drawings, in which—

Figure 1 shows, partly in plan views and partly in elevations, the electric connections of the electro-magnetic registering and signaling instruments with the track-instrument. 60 Fig. 2 is an enlarged detached plan view of the registering-instrument and shunt. Fig. 3 is a side elevation of the same. Fig. 4 is an end elevation of said instrument. Fig. 5 is a vertical transverse section on line x x , Fig. 3, 65 showing by full lines the position of the levers for closing the shunt, and by dotted lines the operation of said levers for opening the shunt; and Fig. 6 is a vertical transverse section on line y y , Fig. 5 showing the effect of 70 the first movement of the armature produced on the primary lever, which closes the shunt.

Similar letters of reference indicate corresponding parts.

A 'A' represent two track-instruments located at intervals over the length of the railway and dividing the same into blocks or sections, each of said instruments consisting of a suitable lever, a , which in this instance is represented in the form of a T , pivoted at 75 the junction of its arms and having its vertical arm projecting sufficiently above the rail to be encountered and actuated distinctly by the tread of each wheel of the cars passing over the rail. The other two arms project 80 horizontally from the foot of the vertical arm, and underneath these horizontal arms are located suitable electric circuit-breakers, which may consist of yielding and independently-operating metallic bars b b' , connected, respectively, with two separate circuits, of which 85 B B' denote the batteries. The said bars b b' are normally in contact with suitable electric contact-points c c' , and are in such position in relation to the lever a as to cause 90 one of them at a time to receive the pressure of one of the lateral arms of said lever when the latter is tilted by the passing cars, said pressure throwing the bar out of contact with 95 the contact-point.

C C' represent two electro-magnetic registering-instruments, each consisting of a suitable insulated plate or platform, P, on which are mounted two sets of electro-magnets, 5 M M', the magnets M' effecting the counting in of the registering mechanism, and the magnets M the counting out of the same. The armatures of these magnets are pivoted to posts F F at the farther sides of the magnet, o and are formed with extensions or levers E E', which lie with their free ends toward each other.

Between the free ends of the levers E E', and at right angles thereto, is a shaft, d, 5 pivoted on a metallic frame H, secured to the aforesaid platform.

On the shaft d, at a point between the free ends of the levers E E', is fastened a ratchet-wheel, I, and on the said ends of the levers o are pivoted pawls e e', engaging the ratchet-wheel I at opposite sides of a vertical line drawn through the center thereof. By means of pins p, projecting from the pawls and colliding with cams s, secured to the frame H, 5 the pawls are thrown out of engagement with a ratchet-wheel when at their extreme downward movement.

To the top of the free end of each lever E E' is secured a dog, h, which serves to hold the o ratchet-wheel during the intervals between the engagements of the pawl of the other lever. Said levers are forced automatically upward by means of any suitable and well-known power, which in this instance is represented 5 in the form of spring K, and their upward thrust is limited by a cap secured to the frame H and projecting over the free ends of the levers, and set-screws i i, passing through said cap, arrest by their lower ends the upward movement of the aforesaid levers.

On the shaft d, back of the ratchet-wheel I, is fastened a circular collar or disk, l, which is provided with a beveled cam-notch, l', in its periphery, and over the shaft d and parallel 5 therewith is a metallic lever, m, which is pivoted on the metallic frame H to oscillate vertically over the collar I, and has a tooth or cam, m', projecting from its under side and adapted to enter the notch l'.

o Back of the collar l the shaft d is provided with a worm or spiral flange, d', which engages a gear-wheel, n, secured to a shaft, n', journaled in suitable bearings at right angles to the shaft d, and on the shaft n' is also fastened an annular disk or wheel, J, which is provided with a notch, j, in its periphery. From the lever m projects a lug, m'', which is adapted to enter the notch j. The collar l is of such a diameter and the cam m' of such a c depth as to cause said cam when out of the notch l and riding on the periphery of said collar to lift the lever m sufficiently to withdraw the lug m'' from the notch of the wheel J.

5 S S represent electro-magnetic signals, which are to be located in suitable positions to be easily seen by the engineer or person in

charge of the train. Said signals may be of any suitable and well-known construction. The style here selected for an illustration of 70 my invention consists of a plate having an orifice and two pivoted arms, N N, carrying on their free ends disks N' N', respectively at opposite sides of the center of the orifice, which disks are adapted to fall by gravity 75 into position to close the orifice, as illustrated in Fig. 1 of the drawings. The opposite ends of the arms N N constitute armatures of magnets O O, and by the attraction of said magnets the arms N N are swung so as to expose 80 the orifice of the plate, as represented by dotted lines in Fig. 1 of the drawings, and when released from the magnets the aforesaid arms drop by gravity and carry the disks N' N' toward the orifice, so as to close the same, as 85 shown by full lines in Fig. 1 of the drawings.

Thus far the apparatus herein illustrated resembles the apparatus shown in the patent to J. Harper Gibson, hereinbefore referred to.

The electric circuits for operating the described registering-instrument and signal are normally closed, and are formed as follows: From the bars b b of the track-instruments A A' run wires to a battery, B, and from the other bars, b' b', of said instruments run wires to a 95 battery, B'. The circuit making and breaking devices b c of each track-instrument are electrically connected with the magnets M' M' for registering the wheels of the train entering the block or section of road and with the 100 signals S S. The circuit making and breaking devices b' c' of the track-instruments are connected only with magnets M M and battery B', which electrical connections are made in the following manner: From the contact-point c runs a wire, 1, to a binding-post, 50, on the platform P of the instrument C, and from thence is extended a wire, 2, to the binding-post 30 on said platform. A wire, 3, is extended from the latter binding-post to one 110 of the magnets O of the signal S. A wire, 4, runs from the other magnet of the signal to the binding-post 10, from thence a wire, 5, runs to the magnets M', and from thence a wire, 6, runs to binding-post 20 and then to 115 ground. The foregoing being the normal condition of circuit of battery B, and by the circuit through the magnets O O of the signals S S, the latter are held in position to expose the opening in the signal-plate, and thereby 120 indicate "safety." When the circuit is broken by first wheel of train depressing the lever a, the signal S falls by gravity into position to indicate "danger." From the contact-point c' of each track-instrument is extended a wire, 1', 125 to the binding-post 40 on the platform P, and from said binding-post runs a wire, 2', to the magnet M, and from thence the wire 3' runs to the binding-post 20, from which a wire runs to the ground, as before stated, the foregoing 130 being the circuit of battery B.

In connection with the circuit of the battery B, I employ a shunt, V, so arranged in relation to the electric connections of the sig-

nal S as to form a shorter circuit with less resistance direct to the magnets M', and thereby cut the signal out of the circuit, which shunt is operated to a certain degree independently of the registering mechanism and by the first break movement of the armature of the magnets M'. The form of said shunt admits of many modifications, and I therefore do not limit myself in this respect. The preferred form here shown consists of two flexible metallic arms, v v', which are insulated and normally out of contact with each other. A wire, 7, runs from the arm v to the binding-post 10, and a wire, 8, runs from the arm 15 v' to the binding-post 50.

To the frame H is pivoted a two-armed lever, k, one arm of which is by a strap or link, u, connected with an arm, u', projecting rigidly from the lever m. The other arm of the lever k is provided with an insulated head, k', which faces the free end of the spring-arm v. A primarily-acting lever, o, is arranged to operate independently of the registering mechanism, said lever pivoted to the frame 25 H, and is sustained normally in a horizontal position at the side of the spring-arm v by springs x x, extending from opposite ends of said lever, and pins g g, projecting from the side of the levers E E across the under 30 side of the aforesaid springs. From one end of the lever o projects laterally a cam, o', which reaches across the top of the spring-arm v and has its under side beveled or inclined so that a downward movement of the 35 lever o causes the cam o' to crowd the spring-arm v into contact with the companion arm v'.

The operation of the described shunt is as follows: When the apparatus is in its normal 40 condition, the lugs m' m'' of the lever m lie, respectively, in the notches l' and j of the collar l and disk J, and thus the lever m has dropped into a position which causes it to tilt the lever k away from the spring-arm v, and the 45 closed circuit holds the armatures with the levers E E' down, and thus allows the lever o to assume a horizontal position, and the spring-arm v to spring away from its companion arm v' and thereby open the shunt V. Consequently the circuit passes through the 50 magnets O O of the signal and holds the latter in a position to indicate "safety." When a train of cars passes over the track-instrument A toward the instrument A', the lever a 55 of the instrument A becomes tilted distinctly by the passage of each wheel on one side of each car, and by each tilt it depresses the subjacent bar b and throws the same out of contact with the contact-point c, as represented 60 in Fig. 1 of the drawings. Thus each wheel entering the block or section of road to be protected momentarily breaks the circuit through the magnets M'. Each interruption of said circuit causes the magnets M' to release the armature, which is immediately 65 raised by force of the spring K, while the circuit through the other magnets is maintained

intact, and thus the armature thereof retained attracted and the registering mechanism maintained dormant. So soon as a car-wheel 70 has passed over the lever a the latter resumes its normal position and allows the bar b to spring back into contact with the contact-point c, and thereby closes the aforesaid circuit and cause the magnets M' to attract the 75 armature, which, by means of the lever E' and the pawl connected thereto, imparts a partial rotation to the ratchet-wheel I, and thereby sets the registering mechanism in motion. The successive impulses through this circuit 80 cause the armature D of the magnets M' to produce a corresponding oscillation of the lever E', and each downward stroke of the latter imparts a partial rotation to the ratchet-wheel I by the medium of the pawl e. The 85 rotation of said ratchet-wheel and its shaft d, with the collar l attached thereto, causes the cam or lug m' of the lever m to be crowded out of the notch l' of said collar, while the worm d' of said shaft turns the gear n, and 90 with it also the disk J. The lever m is thereby lifted and caused to ride with its cam m'' on the periphery of the disk J. During this operation the first break of the 95 circuit and first release of the armature of the magnets M' before the registering mechanism is actuated causes the lever E thereof to tilt the horizontal lever o, so as to press the spring-arms v' into contact with the arm v. The circuit is then more direct, and has less resistance by passing from the binding-post 30 over wire 8 through shunt and wires 7 and 5 to the magnets M'. The magnets O O of the signals, being thus cut out of the circuit, allow the 100 disks N' N' of the signals to drop into position to indicate "danger," as shown by full lines in Fig. 1 of the drawings. The first reclosing of the circuit by the track-instrument and consequent attracting of the armature of the magnets M' turns the ratchet-wheel I with 105 its shaft d sufficiently to lift the lever m, and thereby tilt the lever k, so as to hold the spring-arm v in contact with the companion arm v' during the subsequent impulses of the 110 circuit. As the train passes over the succeeding track-instrument A, the lever a thereof is tilted successively by the car-wheels in the same manner as before described, and the bar b' is thrown correspondingly out of contact 115 with the contact-point c. This produces successive momentary interruptions of the circuit through the magnets M of the two instruments C C, and said interruptions produce a corresponding oscillation of the lever E, which, by its pawl e, imparts a retrograde movement 120 to the ratchet-wheel I, and this movement of the latter causes the worm d' of the shaft d to turn back the disk J. If the same number of cars pass over the track-instrument A' as 125 passed over the instrument A, the disk J will be turned back to its original position to allow the lugs m' m'' of the lever m to drop, respectively, into the notches l' and j, and when 130 this is effected the lever K will be thrown

back and the lever *o* will assume a horizontal position to allow the spring-plate *v'* to automatically spring out of contact with the plate *v*, and thus allow the circuit to flow to the magnets of the signal and actuate the same so as to indicate "safety." In case one or more cars become detached from the train while between the two track-instruments the lever *a* of the second track-instrument will not be actuated a sufficient number of times to restore the disk *J* to its original position, and consequently the signal will remain in the position in which it was set when the train passed over the first track-instrument, and therefore the detached portion of the train will be protected while remaining in the section or block of road between the two track-instruments. When the train passes from the track-instrument toward the instrument *A*, the same result is produced.

In order to enable others skilled in the art to which my invention pertains to properly comprehend and appreciate my invention and distinguish the same from the apparatus described and shown in the patent to J. Harper Gibson, No. 375,063, dated December 20, 1887, hereinbefore referred to, I would call attention to the following facts, to wit: In the J. Harper Gibson apparatus the branch of the circuit including the signal is partly formed by the registering mechanism and its metallic supporting-frame, and the circuit through the said branch is opened and closed by a shunt consisting of a metal plate, which is brought into contact with the lever *m* when raised by the turning of the collar *l*, crowding the cam *m'* of said lever out of the notch *l'* in the collar, and inasmuch as said collar does not turn until the car-wheel has passed over the track-instrument and allowed the latter to reclose the circuit of the main line, and thereby set the registering mechanism in motion, as hereinbefore described, it is obvious that the electric current continues to pass through the magnets of the signal, and therefore said signal remains in its position to indicate "safety" until the first car-wheel has passed over the track-instrument. Another serious defect of said apparatus consists in the operation of the signal depending upon the perfect working of the registering mechanism. Inasmuch as the cam *m'* and periphery of the collar *l* are both subjected to wear and abrasion, said parts are liable to fail to raise the lever *m* sufficiently to bring the same in contact with the plate *v*, and thus fail to close the shunt and cut out the signal to indicate "danger." All of said defects are obviated by the arrangement of the shunt *V*, herein described, which is closed by the first break of the circuit caused when the first car-wheel strikes the track-instrument, and consequently the signal is caused to move to

its position to indicate "danger" sooner than in the Gibson apparatus, hereinbefore referred to. Furthermore, the operation of the lever *o*, which closes the shunt, does not depend on the movement of the registering mechanism, and consequently the operation of the signal is not affected by any defect in the said registering mechanism.

Having described my invention, what I claim as new, and desire to secure by Letters Patent, is—

1. In combination with the normally-closed circuit, circuit-breaker, electro-magnetic registering instrument and signal in said circuit, and said registering-instrument actuated by electric impulses produced by intermittent closing of the circuit, as described, a shunt normally open and forming then a more direct connection of the signal with the circuit and closed by the first break of the circuit and before the registering mechanism is actuated, as set forth. 75

2. In combination with the normally-closed circuit, circuit-breaker, electro-magnetic registering instrument and signal in said circuit, a shunt normally open and forming then a more direct connection of the signal with the circuit, a primary shunt-closing lever operating independently of the registering mechanism and actuated directly by the release of the armatures of the registering-instrument, and a secondary shunt-closing lever operated by the mechanism of the registering-instrument, as set forth. 85

3. In combination with track-instrument, circuit-breakers, magnets *M' M'* and signal *S* in one and the same circuit, armature *D*, lever *E*, connected to said armature, pawl *e* on said lever, worm-shaft *d'*, ratchet-wheel *I* and notched disk *i* on said shaft, notched wheel *J*, and gear-wheel *n*, operated by said worm-shaft, and the lever *m*, having lugs *m m'* 100 adapted to engage the notched disk and wheel, the metallic spring-arms *v* and *v'*, connected with the circuit and normally apart from each other, the lever *o*, having the cam *o'* across the free end of the arm *v*, the pins *g g*, projecting from the levers *E E* and supporting the lever *o*, and the two-armed lever *k*, pivoted to the frame and having one arm connected with the lever *m* and the other arm facing the free end of the spring-arm *v*, 105 substantially as described and shown. 115

In testimony whereof I have hereunto signed my name, in the presence of two witnesses, at New York, in the county of New York, in the State of New York, this 2d day of July, 120 1888.

THOMAS A. CASEY. [L. S.]
